PROFESSIONAL UNIFORM COAT

Charles F. Paqué, Chicago, Ill.

Application September 24, 1948, Serial No. 148,748

Term of patent 14 years

(Cl. D3—4)

To all whom it may concern:

Be it known that I, Charles F. Paqué, a citizen of the United States, residing at Chicago, in the county of Cook and State of Illinois, have invented a new, original, and ornamental Design for a Professional Uniform Coat, of which the following is a specification, reference being had to the accompanying drawing, forming part thereof.

Fig. 1 is a front elevational view of a professional uniform coat, showing my new design.

Fig. 2 is a rear elevational view of the uniform coat.

Fig. 3 is a fragmentary perspective view of the same.

I claim:

The ornamental design for a professional uniform coat, as shown.

CHARLES F. PAQUÉ.
